UNITED STATES PATENT OFFICE.

MARVIN C. SANDERSON, OF HACKLEBURG, ALABAMA.

SINGLE-TRIGGER MECHANISM FOR DOUBLE-BARREL GUNS.

1,140,003.

Specification of Letters Patent.

Patented May 18, 1915.

Application filed September 26, 1914. Serial No. 863,685.

To all whom it may concern:

Be it known that I, MARVIN C. SANDERSON, a citizen of the United States, residing at Hackleburg, in the county of Marion and 5 State of Alabama, have invented certain new and useful Improvements in Single-Trigger Mechanism for Double-Barrel Guns, of which the following is a specification, reference being had to the accompanying drawings.

This invention relates to new and useful improvements in guns, and particularly to double-barrel guns.

An object of this invention is the provision of a double-barrel gun in which the hammers thereof are operated by a single trigger.

Another object of this invention is the provision of a double-barrel gun which is 20 provided with single trigger mechanism, means being provided to release either hammer before the release of the other hammer.

Still another object of this invention is the provision of a double-barrel single trigger gun which is provided with an adjustable actuating member for engagement with the hammer-holding sears, whereby either 25 sear may be actuated before the other sear, so that the hammers may be operated in any 30 desired order.

With these and other objects in view, as will become more fully apparent as the description proceeds, my invention consists in the novel construction, combination, and 35 in the arrangement of parts to be hereinafter more fully described, claimed, and illustrated in the accompanying drawings, in which—

Figure 1 is a side elevation showing the frame in dotted lines, with the hammers set and the sear actuating member engaged with the right hand sear so that the right hand hammer will be operated before the left hand hammer; Fig. 2 is a view similar to 40 Fig. 1 showing the sear operating member operatively engaged against the left hand sear so that it will be operated prior to the right hand sear; Fig. 3 is a perspective view of the trigger plate showing the trigger and sear selecting means connected thereto; Fig. 45 Fig. 4 is an underside plan view of the device, partly in section, with the trigger plate removed; Fig. 5 is a top plan view of the gun; Fig. 6 is a perspective view of the slid- 50 able sear actuating member; Fig. 7 is a perspec- 55 tive view of one of the springs for engagement with the operating stem of the sear operating member; Fig. 8 is a perspective view of the spring plate for holding the sears in engagement with the hammer disks. 60 Fig. 9 is a detail view showing one of the hammer disks and a spring head and sear engaged thereagainst.

Referring more particularly to the drawings, the numeral 1 designates the frame of 65 the gun, and mounted in the side walls 2 of the frame is a shaft 3 upon which are pivotally mounted the right and left hand hammer-holding sears 4 and 5, respectively. Rotatably mounted in the side walls 2 slightly 70 forwardly of and above the shaft 3 are short shafts 6 upon the outer squared ends of which the hammers 7 are secured and upon the inner ends of which within the frame are mounted the disks 8 against the peripheries of which the forward tapered ends of the hammer-holding sears engage. Formed in the forward end of the frame is a central longitudinally extending block 9 which 75 provides chambers between the side walls of 80 the frame and the side faces of the block, and arranged in each chamber is a coiled expansion spring 10, the rear ends of the springs carrying heads 11 the rear end of each head being provided with an arcuate 85 recess therein which provides a pair of shoulders 12 and 13 which are adapted for engagement against the end walls of arcuate recesses 14 formed in the disks 8. In the periphery of each disk 8 to one side of the 90 recesses 14 formed therein, is a pair of notches 15, the forward ends of the sears being engaged with the rearmost notches in the disks when the hammers are in cocked position or engaged in the foremost notches 95 when the hammers have been tripped to fire the barrels. To hold the forward ends of the sears closely engaged against the peripheries of the disks, a spring plate 16 is secured to the rear end of the block 9, the plate having a pair of rearwardly extending arms 17 which bear against the forward ends of the sears. To limit the movement of the hammers 100 7 when the same are drawn to cocked position, a pin 18 projects radially from each disk 8, 105 the pins being adapted to engage against the sears 4 and 5 when the hammers have reached their cocked position, the pins also serving to force the forward ends of the sears upwardly so that the extremities there- 110

of will engage in the rearmost notches 15 in the disks and securely hold the hammers in cocked position.

Secured over the lower open end of the frame 1 is a trigger plate 19 which is provided with a tang which projects rearwardly of the body portion of the frame, in substantially parallel relation with a tang 20 which extends rearwardly from the top wall of the frame. Projecting upwardly from the rear end of the tang of the trigger plate is a post 21 against which the rear end of the bar 20 engages, the rear portion of the trigger plate being secured in position by disposing a screw 22 through the tang 20 into threaded engagement with the post 21. Extending upwardly from the trigger plate adjacent its forward end is a block 23 which is provided with a pair of spaced apertured lugs 23', between which the forward ends of a pair of spaced vertical webs 24 are engaged, the webs being formed on the trigger 25 which extends downwardly through a slot 26 in the trigger plate. The forward ends of the webs 24 are also apertured and passed through the registering apertures in the lugs 23' and the webs 24 is a pin 24' by means of which the trigger is pivotally connected to the block 23.

Slidably mounted between the upstanding webs 24 is a sear selecting actuating bar or member 27, the bar having a pair of slots 28 therein through which pins 29 extend to limit the sliding movement of the bar with relation to the trigger. The rear end of the bar 27 projects rearwardly of the webs 24 and lies upon the upper face of the trigger plate, thereby preventing downward movement of the webs through the slot 26 in the plate, and formed in the lower edge of the rearwardly projecting portion of the bar 27 is a notch or recess 30 through which the angularly extended lower end 31 of an actuating stem 32 engages. The upper end of the stem 32 projects through a slot 33 in the bar 20, and formed on the upper extremity of the stem is a head 34 by means of which the stem may be moved forwardly and rearwardly in the frame. To normally hold the stem 32 in adjusted position, a pair of bowed springs 35 are engaged at their rear ends in a groove 36 in the post 21, the forward ends of the springs being engaged against the under face of the bar 20 forwardly of the stem, and the opposing edges of the springs having elongated recesses 38 formed therein to provide a slot through which the stem 32 extends, and the stem having a pin 39 projecting laterally therethrough to engage against the lower faces of the springs 35, whereby sliding movements of the head 34 and stem 32 are resisted by the tension of the springs.

The rear end of each sear 5 is provided with an inturned extension 40, the extension

of the left hand sear being disposed above the extension of the right hand sear in parallel relation therewith, and the extensions being disposed above the sear actuating bar 27, the extensions forming the portions of the sears which are engaged by the sear actuating bar. The upper edges of the webs 24 are provided with transversely alined notches 41, the notches being formed on the webs below the inturned ends 40 of the sears, and formed in the upper edge of the bar 27, which is flush with the upper edges of the webs, is a notch 42 which is of the same size as the notches 41 and is adapted to register therewith when the bar 27 is in its rearmost position. Formed on the upper edge of the bar 27 forwardly of the notch 42 is an upstanding stem 43 which is provided at its upper extremity with a rearwardly projecting extension 44, the extension 44 being in a plane for engagement between the inturned ends 40 of the sears.

In the practical use of my device, the selector 27 may be adjusted before or after the hammers are set or cocked, to trip either of the sears before the other sear. When it is desired to fire the left hand barrel first, the head 34 of the stem 32 which is connected with the selector 27 is moved to its rearmost position, thereby moving the sear actuating bar rearwardly to dispose the notch 42 below the inturned end of the right hand sear 5 and the rearward extension 44 of the upstanding stem 43 on the bar 27 below the inturned end of the sear 4. When the parts are in this position, with the hammers cocked and the trigger 25 is pulled, the inturned end of the sear 4 will be raised by the rearwardly extending projection 44, of the upstanding stem 43 whereby to disengage the forward end of the sear 4 from the rearmost notch 15 in the disk 8 of the left hand hammer so that the spring 10 acting through head 11 against the disk of the left hand hammer will rotate the same to fire the left hand barrel. Owing to the registering notches 41 in the webs 24 and the notch 42 in the upper edge of the sear actuating bar, the inturned end of the sear 5 will not be engaged until after the sear 4 has been tripped, and upon a continued pull upon the trigger the inturned end of the sear 5 will be engaged by the base walls of the registering notches to raise the inner end of the sear 5 and disengage the forward end of the sear from the disk of the right hand hammer so that the right hand barrel will be fired.

After the gun has been reloaded and it is desired to fire the right hand barrel prior to the left hand barrel, the head 34 is moved to its foremost position so that the sear selector 27 will be moved forwardly between the upstanding webs of the trigger, whereby the rearwardly projecting extension 44 will be moved forwardly of the inturned ends

of the sears and the upper edge of the bar 27 rearwardly of the notch 42 will be disposed immediately below the inturned end 40 of the sear 5. With the sear actuating bar in this position, when the trigger is pulled, the sear 5 is first actuated by reason of the engagement of the bar 27 with the inturned end of the sear, to fire the right hand barrel first. The space between the inturned ends 40 of the sears is sufficient to allow the firing of the right hand barrel before the end 40 of the sear 5 engages the inturned end of the left hand sear 4, and upon a continued pull on the trigger, the engagement of the inturned end of the sear 5 with the inturned end of the sear 4 will actuate the left hand sear 4 to fire the left hand barrel after the right hand barrel has been fired. By the provision of the pins 29 which project through the slots 28 in the sear actuating bar, the sliding movement of the bar 27 with relation to the webs of the trigger is limited and when the pins 29 are disposed in either end of the slots, the bar is then in position to actuate one of the sears prior to the other.

From the above description taken in connection with the accompanying drawings, it will be seen that I provide an extremely simple trigger mechanism for double-barrel guns, in which a predetermined sear may be actuated prior to the other sear either before or after the hammers of the gun are cocked, the sear actuating means being so arranged that both of the barrels may be fired successively upon a continued pull upon the trigger.

Having thus described my invention, what I desire to claim and secure by Letters Patent is;

1. In a single trigger mechanism for double-barrel guns, a pair of parallel sears, each having an inwardly extending lug, said lugs being disposed in vertically spaced registering relation, and a sear actuating and selecting member having a notch and a projecting lug disposed in such relation to each other that when the lug is beneath one sear the notch will be coincidently beneath the other sear, a trigger operatively connected with the actuating member to raise the latter, and means for longitudinally shifting the sear actuating member.

2. In a single trigger mechanism for double-barrel guns, a pair of parallel sears, each having an inwardly extending lug, said lugs being disposed in vertically spaced registering relation and a longitudinally shiftable sear actuating and selecting member

having a notch upon its upper edge and an upwardly projecting lug forward of the notch, said lug having a rearwardly projecting portion at its upper end partially overhanging the notch, the rear end of the notch providing a shoulder adapted, when the actuating member is shifted forward to carry its lug from beneath one sear, to be carried forward beneath the other sear.

3. In a single trigger mechanism for double-barrel guns, a pair of oppositely disposed pivoted sears, a trigger, a medially disposed longitudinally extending sear actuating and selecting member mounted on the trigger, the tails of the sears extending rearward and having laterally extending terminals disposed in overlapping vertically spaced relation, the sear actuating member having a notch and an annular lug disposed in such relation to the notch that when the upper angularly extending end of the lug is disposed beneath one sear the notch will be disposed beneath the other sear, and when the sear selecting and actuating member is longitudinally shifted the angularly extending lug will be disposed out of registration with the first named sear and the shoulder at the rear end of the notch will be disposed beneath the other sear.

4. A single trigger mechanism for double-barrel guns comprising a gun frame, pivoted hammer holding sears having inturned rear ends mounted within the frame, a sear actuating bar slidably connected to the trigger, said sear actuating bar having a notch formed in its upper edge, a stem projecting upwardly from the bar forwardly of the notch, a rearwardly projecting lug formed on the upper end of said stem, said sear actuating bar being disposed below the sears, and the rearwardly extending lug being adapted for engagement with the inturned end of one of the sears, with the notch disposed below the inturned end of the other sear when the bar is in one of its positions, the upper edge of the sear actuating bar adjacent the notch being disposed below the inturned end of said other sear and the rearwardly extending lug being removed from its position below the first mentioned sear when said sear actuating bar is in its other position.

In testimony whereof I hereunto affix my signature in the presence of two witnesses.

MARVIN C. SANDERSON.
